United States Patent Office

Des. 193,427

Patented Aug. 21, 1962

193,427

ELECTRIC CAN OPENER OR THE LIKE

Douglas W. Anderson, Palatine, and Andrew L. Alger,
Evanston, Ill., assignors to Burgess Vibrocrafter, Inc.,
Grayslake, Ill., a corporation of Delaware

Filed Feb. 15, 1962, Ser. No. 68,840

Term of patent 14 years

(Cl. D22—2)

FIG. 1 is a front perspective view of an electric can opener showing our new design;

FIG. 2 is a rear perspective view thereof;

FIG. 3 is a front elevational view thereof;

FIG. 4 is a side elevational view taken from the left of FIG. 3, and

FIG. 5 is a top plan view thereof.

The essential features of our design reside in the portions shown in full lines.

We claim:

The ornamental design for an electric can opener or the like, substantially as shown and described.
